W. KAUFFMAN

OIL BURNER

Filed Jan. 25, 1927

Inventor

WALTER KAUFFMAN

By *W. S. McDonell*

Attorney

UNITED STATES PATENT OFFICE.

WALTER KAUFFMAN, OF COLUMBUS, OHIO.

OIL BURNER.

Application filed January 25, 1927. Serial No. 163,522.

This invention relates to liquid fuel burners and has for its principal object to provide a burner adapted for general uses, so formed as to be simple yet efficient in construction, effective in action, and less expensive to manufacture than burners of ordinary construction and now in general use.

Another important object of the invention resides in the provision of an oil burner designed to secure efficient atomization of the fuel oil to the end of securing perfect combustion at the end of the burner with but the employment of ordinary blast pressures, thus eliminating the use and cost of highly compressed air or high pressure steam heretofore generally used in oil burner designs.

With these and other objects in view, as will appear as the description proceeds, the invention consists in the novel features of construction, combinations of elements and arrangements of parts hereinafter to be fully described and pointed out in the appended claim.

In the accompanying drawing:

25 Figure 1 is a view in side elevation, and partly in vertical section, of the improved oil burner comprising the present invention,

30 Figure 2 is a front view of the spray nozzle or distributing head,

35 Figure 3 is a detail sectional view of the spray nozzle.

Referring more particularly to the accompanying drawings, the numeral 1 designates the casing of the burner. In this instance the casing is formed to comprise an elbow casting 2 which has the vertically extending leg thereof connected with an air blast conduit 3, the latter leading to a source of air supply by which air at a comparatively low pressure, such for example as six ounces per square inch, may be obtained.

40 The horizontal leg of the casting 2 is exteriorly threaded as at 4 for the reception of a collar 5. The outer end of this collar is flanged as at 6 for registration with a similar flange provided peripherally upon a distributor head 7. Passing devices 8 pass through the flanges of the collar and the head to retain the latter elements in secured engagement. A gasket 9 may be situated between said flanges to secure a fluid tight connection.

45 Extending longitudinally and axially through the casting 2 and the collar 5 is a liquid fuel supply pipe 10. The outer end of this pipe passes through a gland 11 pro-

vided in the casting 2 and is connected with the casing of a manually adjusted needle valve 12. An oil supply pipe line 13 is connected with the inlet side of the valve 12 and is adapted to supply the pipe 10 with a suitable quantity of liquid fuel under pressure, the line 13 being provided with a conventional form of oil strainer 14. The oil pressure in the pipe line 13 is such, together with the adjustment of the needle valve, that oil will be forced through the pipe 10 under pressures varying from ten to twenty pounds per square inch.

50 The outlet end of the pipe 10 is provided with a spray nozzle which consists of a cap 15, which is internally threaded for connection with the outer end of said pipe. The front of the cap 15 is provided with a tapering orifice 16 in which is arranged the conical head of a valve 17. The stem of this valve is arranged axially within the outer end of the pipe 10 and is provided with a fixed washer 18. Surrounding the valve and confined between the washer 18 and the front 55 wall of the cap is a coil spring 19, which normally serves to maintain the head of the valve 17 in a seated position within the orifice. However, in the operation of the burner this valve responds to the internal fluid pressures 60 within the pipe 10 and opens the orifice 16 to a greater or lesser degree, depending upon the fuel pressure, so that the oil will be discharged in a finely divided state or in atomized form into the mixing chamber 20 provided in the head 7.

65 Internally the head 7 is provided with a partition wall 21 provided with an axial opening 22 in which the cap 15 is positioned. Additional openings 23 are provided in the 70 wall 21 and establish communication between the air blast conduit and the mixing chamber.

75 In the operation of the burner oil under approximately the pressure specified, is forced through the pipe 10 and past the valve 17, by way of the orifice 16, into the mixing chamber. Due to the formation of the orifice and the cooperative formation of the head of the valve 17, together with the pressures employed, the oil is finely atomized and is in proper condition for admixture with the air and to obtain a state of carburization 80 suitable for efficient combustion. Air is then passed through the air brass conduit, under 85 comparatively low pressures, and due to the conical form of the partition wall 21, and

the position of the openings 23 therein together with the outwardly flaring form of the head of the valves 17 it will be seen that, in operation, a thorough commingling of the liquid fuel in spray form with the incoming air will be effected because of the intersecting fluid streams, thereby bringing about a condition making for efficient carburization of the fuel together with corresponding complete combustion. By this arrangement I have provided a burner which operates effectively without employing compressed air, high pressure steam or other more expensive atomizing mediums. The parts of the burner are of extremely simple construction, of long life and durability and not likely to become out of order or to require any unusual attention in maintaining perfect operation thereof.

It is obvious that variations in the details of construction and arrangements of parts may be made without departing from the spirit or principles of the invention, and therefore I do not wish to be limited to such specific features, except as hereinafter particularly required by the claim.

What is claimed is:

An oil burner embodying a low pressure air blast conduit, a distributing head removably carried by the outer end of said conduit and formed to include a forwardly converging mixing chamber, a wall formed integral with the inner end of said head of substantially conical form, said wall being provided with openings establishing communication between said chamber and said air blast conduit, the axes of said openings intersecting the axis of said chamber, and oil supply pipe passing longitudinally through said conduit, a spray nozzle carried by the outer end of said pipe and communicating with the inner end of said chamber, said nozzle being formed to include a discharge orifice, and a spring pressed valve serving normally to close said orifice but responsive to fluid pressures within said pipe to admit of the passage of oil through said orifice to inject the oil in spray form into said chamber.

In testimony whereof I affix my signature.

WALTER KAUFFMAN.
